United States Patent

Des. 237,023
Patented Oct. 7, 1975

237,023

HIGH CHAIR

Joseph V. Rossi, Chicago, Ill., assignor to Comfort
Lines, Inc., Chicago, Ill.

Filed Mar. 27, 1974, Ser. No. 455,119

Term of patent 14 years

Int. Cl. D6—01

U.S. Cl. D6—8

Fig 2

Fig 3

Fig 4

FIG. 1 is a perspective view of a high chair showing my new design;

FIG. 2 is a front elevational view of the high chair shown in FIG. 1;

FIG. 3 is a side elevational view of the high chair shown in FIG. 1;

FIG. 4 is a top plan view of the high chair shown in FIG. 1;

FIG. 5 is a rear elevational view of the high chair shown in FIG. 1; and

FIG. 6 is a bottom plan view of the high chair shown in FIG. 1.

I claim:

The ornamental design for a high chair, substantially as shown.
